(57) **CLAIM**

The ornamental design for a claw machine as shown and described.

DESCRIPTION

FIG. 1 is a top, front and right side perspective view of a first embodiment of a claw machine, showing my new design; FIG. 2 is a bottom, rear and left side perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a top, front and right side perspective view of a second embodiment of the claw machine;

FIG. 10 is a bottom, rear and left side perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a top, rear and right side perspective view of a third embodiment of the claw machine;

FIG. 18 is a bottom, front and left side perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof; and,

FIG. 24 is a bottom plan view thereof.

The dash-dash broken lines in the drawings depict portions of the claw machine that form no part of the claimed design.
